An insecticide electric apparatus having a body with an upper portion of a semi-circular outline and a wide front opening, comprising one or more of the ornamental features hereinbefore described and/or highlighted in the accompanying illustrations.

DESCRIPTION

FIG. 1 is a front perspective view of an insecticide electric apparatus having a body with an upper portion of a semi-circular outline and a wide front opening showing a design.

FIG. 2 is a side perspective view thereof;

FIG. 3 is a rear perspective view thereof;

FIG. 4 is a front view thereof;

FIG. 5 is a rear view thereof;

FIG. 6 is a top view thereof;

FIG. 7 is a bottom view thereof;

FIG. 8 is a left side view thereof; and,

FIG. 9 is a right side view thereof.
